LADY'S FOUNDATION GARMENT

Sigmund W. Kunstadter, Chicago, Ill., assignor
to The Formfit Company, Chicago, Ill., a corpora-
tion of Illinois

Application March 22, 1950, Serial No. 151,197

3 Claims. (Cl. 2-37)

1

This invention relates to ladies' foundation garments which are in the nature of girdles encompassing substantially the lower torso, hip joints and upper thigh portion and in which the component sections comprise vertical front and rear panels of relatively non-elastic or non-stretchable material, and vertical side panels overlying the hip joints of elastic stretchable material, usually an elastic basket-type porous weave.

It is one object of this invention to provide in such a girdle stretch-modifying means without requiring a change in its basic construction or in the basic shape or cut of the panels; more specifically to provide stretch-modifying means for selectively controlling the stretch resistance of the elastic panels horizontally in such a manner that additional compressive effect, normally not present with the girdle and the panels as cut, is attained in one selected horizontal zone and not in another, as for the purpose of increasing the stretch resistance in an intermediate zone while relatively diminishing the stretch resistance towards the top and towards the bottom of the girdle, in a manner which does not interfere with the comfort of the wearer; or further particularized, to provide such stretch-modifying means whereby a maximum or gentle peak elastic compressive effect is attained in an intermediate horizontal zone surrounding the hip joints and the buttocks of the wearer, with such compressive effect decreasing upwardly and downwardly from the peak in keeping with requirements for the wearer's comfort, this for the purpose of compressing and gently forcing aside or flattening the fleshy part of the buttocks while graduating the release or decompression thereof.

These objects are attained by superimposing upon each elastic side panel and rendering unitary therewith a stretch-modifying or stretch-diminishing patch-like element of elastic material of a shape so predetermined as to effect a graduated change of horizontal stretch-resistance of the elastic panels to meet the requirements such as set forth above with respect to certain desired elastic compressive effects.

According to one feature the stretch-modifying element is a vertically-extending upwardly-pointed tongue-shaped element superimposed upon a side panel and having its rear vertical edge embodied in the vertical seam that connects the rear panel with the side panel, the width of the elements varying in such a manner as to produce the desired change in stretch re-

2

sistance of the panel. More specifically, the tongue-shaped element has its forward vertical edge shaped with a shallow indentation defining a pair of shallow lobes characterizing one embodiment of the shape and appearance of this element.

Briefly this invention comprises an improvement in a girdle-like garment of the type that is adapted to encompass the wearer's lower torso, 10 hip joints and upper thighs, and having substantially non-elastic and non-stretchable vertical front and rear panels and elastic stretchable vertical side panels overlying respective hip joint portions. The improvement provides 15 means for modifying the stretchability of selected portions or areas of the elastic panels, comprising a stretch-modifying partial layer of elastic material fastened to and functionally embodied in each elastic panel, the shape of 20 the partial elastic layers being so chosen that in the desired areas the resistance to horizontal stretch of the panel is relatively increased in a measure corresponding to variations of elastic compressive force required for the purpose as 25 herein set forth.

With the above and other objects in view, the invention consists in the construction and novel combination and arrangement of parts herein-after fully described, illustrated in the accompanying drawings and pointed out in the claims 30 hereto appended, it being understood that various changes in the form, proportions, and minor details of construction, within the scope of the claims or equivalents of their requirements, 35 may be resorted to without departing from the spirit or sacrificing any of the advantages of the invention.

Figure 1 is a front view of the girdle with a front portion broken away to expose part of the 40 stretch-modifying element.

Figure 2 is a rear view of the girdle showing the symmetrical disposition as well as the shape of the stretch-modifying element.

Figure 3 is a side view of the girdle taken on line 3-3 of Figure 1.

Figure 4 is an enlarged partial cross section on line 4-4 of Figure 3.

Figure 5 is a graph illustrating the stretch resistance characteristics of the elastic side panels which have the stretch-modifying elements embodied therein.

Figure 6 shows a modified island-like disposition of the stretch-modifying element on an elastic side panel, illustrating the underlying 55 concept of the invention.

Figure 7 is a stretch resistance graph illustrating the stretch resistance characteristics of the stretch-modifying elements of Figure 6.

Figure 8 is an enlarged partial cross section on line 8-8 of Figure 6.

Figure 9 is a partial top end view of the girdle shown in Figure 6, although with the stretch-modifying element off the panel although adapted to be fastened thereto.

In the Figures 1, 2, 3 embodiment of the invention the girdle is represented as comprising as basic component sections a rear panel 10 and a front panel 11 both of non-elastic and substantially non-stretchable material, and a pair of side panels 12 and 13 of elastic stretchable material.

The side panel 12 is symmetrically similar to the opposite side panel 13 and has its forward edge joined to the front panel by a vertical and substantially straight seam connection 14 while its rearward edge is joined to the rear panel by a vertical although shallow S-shaped seam connection 15, giving the side panel a slightly trapezoidal appearance with a narrower width a at the top and a wider width b at the bottom. The opposite side panel 13 has a forward seam connection 16 and a rearward seam connection 17 defining its shape.

The basic configuration as well as the dimensioning of the stretchable side panels relative to the non-stretchable intervening panels is such as to provide maximum comfort for the wearer when walking or sitting. Indeed for the sake of comfort the front panel has at the bottom an elastic stretchable wedge-shaped insert 18, while the rear panel 10 has its upper corners 10^a and 10^b replaced with elastic stretchable material instead of non-stretchable material. While the rear panel has been described above as consisting of a non-stretchable material, it should be understood that such material may be of the kind that is stretchable in the vertical direction, but non-stretchable in the horizontal direction.

It will thus be noted that the rear panel 10 has a top edge of considerably reduced width c as compared with a width d of the bottom edge. The front panel 11 (see Figure 1) has a top edge of the width e which is somewhat narrower than the bottom width f . The lateral edges or seams of the front panel appear slightly convex with a shallow outward bulge.

The side panel 12 has functionally associated therewith and embodied therein a stretch-modifying element 19 of elastic material, which material may be of the same kind as the elastic material of the side panel, namely, an elastically stretchable porous basket weave. The element 19 in effect constitutes a partial additional layer of such material rendered unitary with the panel as by its rearward seam coinciding with seam 15 and by its forward seam 20 shown to present a pair of shallow lobes 20^a and 20^b defining between them a shallow indentation 21.

The stretch-modifying element 19 has a pointed upper end terminating a distance D_1 from the top edge of the girdle and a bottom end defined by a horizontal bottom edge of a width g and constituting part of the bottom edge of the girdle. The indentation 21 may be said to define the element 19 as comprising a relatively shorter upper portion or lobe vertically measured as of a length h and of a relatively longer or lower portion vertically measured as of a length i . A similar stretch-modifying element 22 is embodied

in the side panel 13 and disposed symmetrically with respect to element 19.

The graph in Figure 5 illustrates in terms of, say, absolute stretch per pound of horizontal pull, the manner in which the elements 19 and 22 modify the resistance to a horizontal stretching force of the elastic side panels by comparison with the stretchability of the unreinforced or bare panels. Hence, the line L_1 in this graph represents the stretchability as measured on the abscissa due to a horizontally effective stretching unit force at any distance measured along the ordinate. Thus S_1 measured on the abscissa represents the stretchability of the panel at its top edge of the bare panel, while S_2 being larger than S_1 represents the stretchability of the bare panel at its bottom edge.

The line or curve L_2 in the Figure 5 graph represents the stretchability of the side panel as modified by the elastic elements 19 and 22, respectively, of the side panels. As a net result due to reinforcement of this kind each panel acquires the characteristics of stretchability, that is of resistance to the stretching force, as approximately indicated by distances S_3 , S_4 , S_5 marking characteristic turning points in the line L_2 . These stretch characteristics are selective in that they result from the particular shape of the symmetrical elements 19 and 22 chosen, and of which the Figure 5 shape of line L_2 constitutes a representative example for obtaining a desired although gentle and graduated elastic compressive effect upon the wearer's buttocks and thighs, while configuration and size of the area of elasticity of the side panels as a whole is being maintained unchanged for the sake of the wearer's comfort of movement.

The Figure 6 embodiment of the invention points up in a different way the concept of how to modify and control the stretch resistance (that is the resistance to a horizontally directed stretching force) of the elastic side panels by the very shape of the superimposed reinforcing element or partial layers of elastic material added to and rendered functionally unitary with the side panels. This embodiment shows a stretch-modifying element 23 which is in the nature of a vertically elongated island occupying an intermediate rather than a marginal portion of a side panel 24. The Figure 7 graph coordinated to the Figure 6 embodiment shows by the comparative lines or curves L_3 and L_4 (corresponding to the Figure 5 lines L_1 and L_2) the characteristics of controlled stretchability of the elastic side panel thus reinforced.

Figure 9 in showing the element 23 detached from although in position for attachment to the elastic side panel 24, further points up the gist and concept of this invention.

60. What I claim is:

1. A foundation garment adapted to encompass the wearer's lower torso, hip joints and upper thighs, the garment having vertical front and rear panels, and elastic stretchable vertical side panels with vertical seam connections between the side panels and the front and rear panels, means for modifying the stretchability of selected portions of the elastic panels comprising a stretch modifying partial layer of elastic material fastened to and embodied in the elastic panel, the partial layer being attached to the lower horizontal edge and extending to a point adjacent the top of the elastic panel and having a shallow indentation on at least one edge thereof defining a shallow upper

lobe and a shallow lower lobe with the upper lobe being shorter than the lower lobe, whereby the shape of the partial layer being such that a resistance to stretch horizontally of the elastic panel is relatively increased in view of variations of elastic compressive force placed thereon by the partial layer with such resistance following generally the outline of the partial layer.

2. A foundation garment as set forth in claim 1 wherein the partial layer has one substantially vertical edge extending along the rearward seam connection of the elastic panel with the rear panel, the vertical edge being embodied in the rearward seam connection.

3. A foundation garment as set forth in claim 1 15 wherein the partial layer is entirely within the

elastic panel and embodied therein on all of its edges.

SIGMUND W. KUNSTADTER.
